United States Patent Office

Des. 199,998

Patented Jan. 5, 1965

199,998

LAMP HOLDER

Leonard Atkin, Springfield, and Richard Sangiamo, Roselle Park, N.J., assignors to Stonco Electric Products Company, a corporation of New Jersey

Filed Nov. 26, 1963, Ser. No. 77,556

Term of patent 14 years

(Cl. D48—20)

FIG. 5.

FIG. 6.

FIG. 7.

We claim:

The ornamental design for a lamp holder, substantially as shown.
